UNITED STATES PATENT OFFICE

152,387

DESIGN FOR A COMPARATOR

Herbert Rosengren, Woodcliff Lake, N. J., assignor to The Jones & Lamson Machine Company, a corporation of Vermont

Application November 21, 1947, Serial No. 142,716

Term of patent 14 years

(Cl. D57—1)

To all whom it may concern:

Be it known that I, Herbert Rosengren, a citizen of the United States and a resident of Woodcliff Lake, in the county of Passaic and the State of New Jersey, have invented a new, original, and ornamental Design for a Comparator, of which the following is a specification, reference being had to the accompanying drawing, forming a part thereof.

Figure 1 is a front perspective view of a comparator, showing my new design; and

Figure 2 is a perspective view of the opposite side, as shown in Figure 1.

I claim:

The ornamental design for a comparator, substantially as shown.

HERBERT ROSENGREN.
